(57) **CLAIM**

The ornamental design for a display screen with graphical user interface, as shown and described.

DESCRIPTION

FIG. 1 is a front view of a display screen with graphical user interface, according to a first embodiment; and, FIG. 2 is a front view of a display screen with graphical user interface, according to a second embodiment.

The broken lines form no part of the claimed design. The outer rectangle in broken lines illustrates the display screen and forms no part of the claimed design. The portions of the graphical user interface shown in broken lines form no part of the claimed design.
